CLAIM

The ornamental design for an LED module, as shown and described.

DESCRIPTION

FIG. 1 is a top view of a first embodiment of an LED module, showing our new design;

FIG. 2 is a bottom view thereof;

FIG. 3 is a left side view thereof;

FIG. 4 is a right side view thereof;

FIG. 5 is a front view thereof;

FIG. 6 is a rear view thereof; and

FIG. 7 is a perspective view thereof.

FIG. 8 is a top view of a second embodiment of an LED module, showing our new design;

FIG. 9 is a bottom view thereof;

FIG. 10 is a left side view thereof;

FIG. 11 is a right side view thereof;

FIG. 12 is a front view thereof;

FIG. 13 is a rear view thereof; and,

FIG. 14 is a perspective view thereof.

The broken lines in the drawings illustrate portions of the LED module and form no part of the claimed design.

1 Claim, 7 Drawing Sheets
